CLAIM

The ornamental design for a hip abduction pillow, as
shown and described.

DESCRIPTION

FIG. 1 is a perspective view of a hip abduction pillow,
embodiment of my present invention;

FIG. 2 is a top plan view thereof;

FIG. 3 is a front elevational view thereof;

FIG. 4 is a right side elevational view thereof (left side
being a mirror image);

FIG. 5 is a rear elevational view thereof; and

FIG. 6 is a bottom plan view thereof.

FIG. 1.

FIG. 2.

FIG. 3.

FIG. 4.

FIG. 5.

FIG. 6.
